UNITED STATES PATENT OFFICE.

GUSTAVE E. W. MILLER, OF BOSTON, MASSACHUSETTS, ASSIGNOR TO SCOVILL MANUFACTURING COMPANY, OF WATERBURY, CONNECTICUT, A CORPORATION OF CONNECTICUT.

SHAVING-SOAP STICK AND HOLDER.

Application filed September 28, 1922. Serial No. 591,166.

To all whom it may concern:

Be it known that I, GUSTAVE E. W. MILLER, a citizen of the United States, residing at Boston, in the county of Suffolk and State 5 of Massachusetts, have invented a new and useful Shaving-Soap Stick and Holder, of which the following is a specification.

The principal objects of this invention are to provide a combined holder and soap stick in an inexpensive and easily manufactured form with a connection between them that will securely hold the stick in position but will permit the stick to be removed when practically used up and a new 10 one substituted for it, thus eliminating the necessity of going to the expense of purchasing a new holder each time a shaving stick is needed.

One of the other objects of this invention 15 is to provide a holder simple in construction, easily assembled, consisting of few parts and provided with means whereby the soap stick is easily attached and detached from it but is firmly mounted on it when 20 in use; also a holder of such a nature as to be complete in itself, attractive to the eye and convenient for use and to provide it with a flat bottom so that it can be stood up on end and of such a nature as not to 25 corrode and be injured by the alkali of the soap.

Reference is to be had to the accompanying drawings, in which—

Fig. 1 is an elevation of a soap stick and 30 holder constructed in accordance with this invention with the holder partly broken away to show the connection between the two;

Fig. 2 is a similar view of the soap stick 35 entirely removed from the holder;

Fig. 3 is a perspective view of the holder and anchor;

Fig. 4 is a view similar to Fig. 1, showing 40 a modification;

Fig. 5 is a view of the soap stick slid out to one side and removed;

Fig. 6 is a plan of the holder with the soap stick removed; and

Fig. 7 is a side view of the same.

I am aware of the fact that shaving sticks 50 and holders have been made in which the whole thing would have to be discarded after the stick was used up. This invention does not relate to that type of device.

In the form shown in the first three fig-

ures, the holder involves two pieces, a bottom 10 and a top 11, each of sheet metal. Both are made up in cup-shape form and the lower one set into the bottom of the upper one with its flange uppermost so that 60 both ends of the holder are closed. The larger drawn metal cup has a flat end which constitutes the top of the holder and is also provided with an auxiliary circular disc 14 which is of noncorrosive metal. This disc 65 also can be made of non-metallic material. Its principal object is to prevent corrosion of the holder.

The top of the holder and the auxiliary 70 disc have a slot 12 preferably diametrically cut through them for receiving the anchor 13 which goes through both of them. This anchor consists of a piece of flat sheet metal doubled over to provide a T-shape 75 shank having two legs in contact through the slot 12. The legs are spread out at the bottom under the top of the holder before the bottom cup 10 is applied in a securely fixed position. This anchor is made of a 80 single piece of non-corrosive metal.

The larger or upper cup which constitutes the upper part of the holder is made with straight sides having two shoulders of different dimensions. One shoulder 15 is 85 for receiving a guide collar 16 which slips over the soap stick and then is screwed over a screw thread on the straight part of the cup 11. The other shoulder 17 of this cup has three or more notches protruding outward which act as rests or rather as feet for supporting the device. It will be seen that the bottom of the holder consisting of the cup 10 rests with its edges against the inside of the bottom shoulder of the outer cup and the feet turned up against the bottom edge 90 of this cup. The lower edge of the large cup is pressed over the closed end of the bottom cup 10 so that the holder is securely closed at both ends.

The guide collar 16 screws on the holder 95 and receives the soap stick 20 within its cylindrical upper flange and fits closely against it so that the soap stick is held from tipping sideways. It does not, however, have any means for preventing the stick moving up and down, that is, toward or from the holder or base. It is to be noted also that it does not act as a fastener for the soap stick as it does not fasten it to the holder in any way nor does it have any- 105 110

thing to do with detaching the stick from the whole top. It has no holding function except to prevent side movement but it gives the soap stick and holder the necessary finish 5 to make it attractive to the eye and it furnishes a convenient surface for handling the soap stick. It is made of a non-corrosive metal, preferably aluminum.

The soap stick 20 is provided with a diametrical or otherwise undercut slot 21 therein of the same shape and size as the anchor 13. This is so located that when the guide collar is removed by unscrewing it and taking it off the end of the soap stick the latter 15 can be removed from the holder by sliding it sideways along the anchor 13. The anchor is headed over at the top and it is received through the undercut recess to hold the soap stick against longitudinal motion 20 away from the base or holder. Thus, the soap stick is prevented from motion in all directions when in place on the holder and when the guide collar is also in place. This 25 constitutes an anchor for securely holding the soap stick and for guiding it off and on with a sideways motion.

It will be understood, of course, that other forms of undercut holding devices can be employed as I have shown herein in Figs. 4, 30 5, 6 and 7. This construction consists simply in the provision of the top of the base or holder with a bent over arcuate flange 30 spaced from the base and extending not over half way around it. The soap stick is 35 formed with a similarly shaped recess 31 extending the same distance around it for receiving this horizontal flange 30 within it. It performs the same function as the T-shaped anchor shown in the other figures 40 and substantially in the same way.

From what has been said, it will be seen that I have provided a device consisting of few parts easily made and assembled which will permit of the soap stick being placed 45 on a base or holder by any unskilled person and permit its being placed only in one position thereon. The soap stick is securely held from motion in one direction by the anchor and from motion in the transverse 50 direction by the guide collar. When assembled, the soap stick is used in exactly the ordinary way and when it is used up the butt of it can be removed very easily and a new one put in its place without going to the expense of buying a new holder or base. It is inexpensive and attractive and can be 55 used on soap sticks for shaving and also for other solid sticks for various purposes, as for medicines or the like and, in fact, it can be used for a menthol or rouge stick or for a lubricating compound in stick form and for many other purposes.

Although I have illustrated and described 60 only two forms of the invention, I am aware of the fact that other modifications can be 65

made therein by any person skilled in the art without departing from the scope of the invention as expressed in the claims. Therefore, I do not wish to be limited to the exact forms herein shown but what I do 70 claim is:—

1. As an article of manufacture, a base for holding a detachable article having a flat closed top and bottom and provided with an anchor extending upwardly therefrom from 75 said top and laterally projecting at its upper end for securing the article thereto in a position to be removed by a sliding motion along said top.

2. As an article of manufacture, a base for 80 a soap stick or the like, comprising a sheet metal portion having a flat closed top and bottom and circular in cross-section and provided with an anchor extending upwardly therefrom from said top and laterally 85 projecting at its upper end for securing a soap stick thereto.

3. As an article of manufacture, a base for a soap stick or the like, comprising a portion having a flat closed top and bottom 90 and provided with an anchor extending upwardly therefrom from said top for securing a soap stick thereto, said anchor having a T-shaped construction.

4. As an article of manufacture, a sheet 95 metal holder comprising two cup-shaped parts, the upper part having an open bottom and the lower part an open top and closed bottom, the lower part setting into the bottom of the upper part, whereby said 100 holder is closed at the bottom and top, and means on the top of said holder for detachably holding a soap stick or the like in position to move therefrom by a sideways diametrical motion.

5. As an article of manufacture a sheet metal holder comprising two cup-shaped parts, the upper part having an open bottom and the lower part an open top and closed bottom, the lower part setting into the bottom of the upper part, whereby said 110 holder is closed at the bottom and top and a T-shaped anchor on the top of said holder for a soap stick or the like having a T-shaped slot, whereby the stick can be supported on the holder in position to move therefrom by a sideways diametrical motion.

6. As an article of manufacture a holder 115 for a soap stick having a recess near one end, comprising an anchor having an offset portion located in said recess for holding the soap stick thereon, said soap stick being capable of being detached from the holder and anchor by a motion in a plane parallel 120 to the top of the holder.

7. As an article of manufacture a holder 125 for a soap stick having a recess near one end in a plane parallel with said end, comprising an anchor having a flat offset por- 130

tion projecting above the top thereof and located in said recess for holding the soap stick thereon, whereby said soap stick is capable of being detached from the holder 5 and anchor by a motion in a plane parallel to the top of the holder.

8. As an article of manufacture a shaving soap stick device, comprising a base having an anchor projecting upwardly from the 10 top thereof and provided with an overlapping top for a soap stick having an undercut recess therein for receiving said anchor and preventing the soap stick from motion directly away from said base, and means 15 mounted on said base and overlapping the bottom of the soap stick for preventing the soap stick from being moved laterally.

9. As an article of manufacture a shaving soap stick device, comprising a circular base 20 having an anchor projecting upwardly from the top thereof and provided with an overlapping top for a soap stick having an under-

cut recess therein for receiving said anchor and preventing the soap stick from moving directly away from said base, and a circular 25 collar mounted on said base and overlapping the bottom of the soap stick for preventing the soap stick from being moved laterally.

10. The combination with a base having a 30 flat top and an upwardly projecting anchor for a soap stick having a recess extending up into it to receive said anchor, said base being circular, of a collar screwed on the top of the base and projecting upwardly 35 therefrom and having an interior diameter just fitting the soap stick so that the soap stick will be held frictionally therein and prevented from detachment from the base when the collar is screwed up into position. 40

In testimony whereof I have hereunto affixed my signature.

GUSTAVE E. W. MILLER.
